UNITED STATES PATENT OFFICE

HARRY DIXSON, OF PELLA, IOWA, ASSIGNOR TO ROLSCREEN COMPANY, OF PELLA, IOWA

CASING-SUPPORTING AND TRACK-RECEIVING DEVICE

Application filed October 22, 1928. Serial No. 314,115.

The object of my invention is to provide a casing supporting and track receiving device of simple, durable and comparatively inexpensive construction.

5 A further object of my present invention is to provide a device adapted for installation in a window opening of a building after the building has been erected and one which serves to support a screen casing having a 10 flexible rolling screen therein and also serves to receive guide tracks for the side edges of the rollscreen.

Still a further object is to provide such a device which may be easily installed and when 15 installed will serve to support both the rollscreen casing and the guide tracks without further means of attachment being provided for the casing and the tracks.

More particularly it is my object to provide 20 a device of the character herein disclosed, comprising supporting portions adapted to be secured against the sides of a window opening and have a rollscreen casing supported on their upper ends, the device 25 also having moulding portions for giving them a finished appearance and having grooves formed in them substantially between the moulding portions and the supporting portions, the grooves being provided 30 for receiving guide tracks for the rollscreen when it is extended from the rollscreen casing.

Still a further object is to provide the 35 moulding portions of the device of greater length than the supporting portions whereby the moulding portions contact with a surface of the rollscreen casing which projects toward the inside of the building and thereby prevents displacement of the rollscreen casing from the supporting portions of the device.

Still a further object is to provide a connecting moulding for giving a finished appearance to the installation, the connecting moulding extending from the moulding portion 45 of the device on one side of the window opening, to the moulding portion of the device on the other side thereof.

With these and other objects in view my 50 invention consists in the construction, arrangement and combination of the various

parts of my device, whereby the objects contemplated are attained, as hereinafter more fully set forth, pointed out in my claims, and illustrated in the accompanying drawings, in which:—

Figure 1 is an inside elevation of a window in a window opening of a building and illustrates a rollscreen assembly in connection with my casing supporting and track receiving device which is applied thereto.

Figure 2 is a horizontal sectional view on the line 2—2 of Figure 1.

Figure 3 is a perspective view of a piece of my casing supporting and track receiving device.

Figure 4 is a perspective view of a rollscreen casing and two of my devices associated therewith for supporting the same.

Figure 5 is an enlarged fragmentary sectional view on the line 5—5 of Figure 1.

Figure 6 is a perspective view of an end of a rollscreen casing, illustrating my device associated therewith.

Figure 7 is a perspective view of the upper end of one of my devices; and

Figure 8 is an enlarged sectional view on the line 8—8 of Figure 1, illustrating my device in section and a rollscreen track associated therewith for the purpose of showing the parts more in proportion than is possible in the smaller sectional view illustrated in Figure 2.

On the accompanying drawings 1 have used the reference character 10 to indicate a wall. The wall 10 is provided with a window opening 12 and in connection with my Figures 1 and 5, I show a ceiling 14. The member 16 is a picture moulding extending along the wall 10.

A sill 18 defines the lower end of the window opening 12 and in connection with the window opening I have illustrated a window frame consisting of a bottom frame member 20, a top frame member 22 and side frame members 24. The window frame also includes a center frame member or mullion 26.

A pair of the windows 28 are illustrated in connection with my drawings. The windows 28 may be of the type hinged at the center to swinging bars which are concealed

in the lower and upper frame members of the windows themselves and hence do not show on the drawings. It is obvious of course, that they can be of any other type such as the 5 swinging type hinged at their side edges and my device may also be applied to sash type windows.

The rollscreen assembly with which my device is used, consists of a screen casing A, 10 rollscreen 30 and guide tracks B. The rollscreen 30 is attached at its inner end to a roller within the casing A and is attached to a spacer or binder bar 32 at its outer end. The side edges of the screen 30 are normally 15 adapted to travel in enlarged tubular portions 34 of the guide tracks B and the binder bar 32 is provided with enlarged tubular ends or friction blocks 36 which also travel in the tubular portions 34 of the guide 20 tracks B.

As clearly shown in Figures 2 and 8 of the drawings, slits are formed in the tubular portions 34 of the guide tracks B for the screen 30 and reduced portions of the friction 25 blocks 36 to extend through. The side edges of the screen 30 are provided with staples 31 or other devices for providing enlargements to normally prevent pulling of the side edges of the screen from the guides B.

30 My improved casing supporting and screen receiving device C consists of a channel shaped supporting portion having a web 38 and flanges 40 and 42. Spaced openings 44 are formed throughout the length of the 35 supporting portion of the device C. The device C also includes a moulding portion formed by a flange 46 and a return flange 48 of irregular configuration simulating some type of wood moulding as generally used in 40 finishing the construction of window frames, etc.

The portions 46 and 48 form a moulding portion of substantially channel shaped construction which opens in the same direction 45 as the channel shaped supporting portion of the device. Referring to Figures 6 and 7 of the drawings, it will be noted that the moulding portion 48 extends beyond the supporting portion as indicated at 46^a and 48^a for a purpose which will hereinafter be fully described.

50 The flanges 42 and 46 form a groove opening in a direction opposite to the channel shaped supporting and moulding portions of 55 the device C for the purpose of receiving a flange 50 formed on the guide track B. The spacing between the flanges 42 and 46 is such as to cause frictional engagement between these flanges and the flange 50 of the 60 guide track B.

The upper end of the moulding portion is cut away at an angle as indicated at 46^b and 48^b whereby a connecting moulding member 52 may have its end interfitting therewith.

65 In the installation of my device, the casing

A is held adjacent the top of the opening 12 in the wall 10 and two of the devices C are inserted beneath the casing whereby their webs 38 contact with the bottom of the casing A adjacent its ends for supporting the 70 same relative to the window opening 12.

The portions 46^a and 48^a of the device extend up to engage the inside surface of the casing A adjacent its ends as clearly shown in Figures 1 and 6 of the drawings. Screws 75 or other fastening elements 54 are then used for connecting the devices C with the sides of the window opening 12.

The connecting moulding 52 is installed across the window opening from side to side 80 thereof and adjacent the upper inner edge of the casing A. The connecting moulding 52 is provided for the purpose of giving a finished appearance to the installation but may be dispensed with if desirable.

85 The flanges 50 of the guide tracks B are then inserted in the grooves formed by the flanges 42 and 46 of the devices C, the binder bar 32 having its friction blocks 36 inserted in the guide tracks as they are being received in the supporting and receiving devices C. The binder bar 32 is then pulled downwardly by the operator which threads the side edges of the screen 30 in the guide 90 tracks B and causes the guide tracks B to move inwardly or outwardly relative to their reception grooves depending on whether the tubular portions 34 thereof are of proper distance apart to receive the friction blocks 36 on the ends of the binder.

95 The dimensions of the various parts of my device are such that the flanges 50 of the guide tracks B do not normally extend to the bottom of their receiving grooves in the devices C so that contraction and expansion caused by temperature changes or other causes, is provided for without affecting the 100 proper operation of the rollscreen.

The entire rollscreen assembly and casing 105 supporting and track receiving devices therefor, may be easily removed from the openings 12 by removing the screws 54. Thus provision is made for easy repair of the screen or replacement of new parts. The casing supporting and track receiving device is of extremely simple construction consisting of a single piece of metal in which the supporting portions are channel shaped so as to extend away from the side of the window opening and thus support the casing A at a slight 115 distance from its ends.

120 This is obviously a desirable advantage since the parts would have to be exact to a certain dimension if the web 38 were flat against the side of the window opening.

125 A further advantage in the channel construction is to provide a flange 42 of substantial width which in conjunction with the flange 46 of the moulding portion of the device, serves to receive the comparatively 130

wide flange 50 of the guide track B. Thus ample provision is made for movement of the flange 50 to compensate for all changes caused by weather conditions, etc.

5 The portion 48 of the device C serves the purpose of providing a neat finished appearance after building the flange 46 out from the side of the wall opening 12 to receive the guide track B.

10 Various changes may be made in the construction and arrangement of the parts of my device without departing from the real spirit and purpose of my invention, and it is my intention to cover by my claims, any 15 modified forms of structure or use of mechanical equivalents, which may be reasonably included within their scope.

I claim as my invention:

1. The combination with a rollscreen assembly including a screen casing and a guide track, of a casing supporting and track receiving device, comprising a supporting portion for said screen casing and a moulding portion, said device having a longitudinal groove formed therein between said supporting and said moulding portions, said groove being adapted to receive the guide track.

2. The combination with a rollscreen assembly including a screen casing and a guide track, of a casing supporting and track receiving device, comprising a supporting portion for said screen casing, a moulding portion and a guide track receiving portion, said receiving portion comprising flanges formed in said device whereby a groove is provided between said supporting and said moulding portions, said groove being adapted to frictionally receive a portion of the guide track.

3. The combination with a rollscreen assembly including a screen casing and a guide track, of a casing supporting and track receiving device, comprising a supporting portion for said screen casing and a moulding portion, said device having a groove formed therein lengthwise of the device and between said supporting and said moulding portions, said groove being adapted to receive the guide track, said moulding portion of said device extending above the supporting portion thereof and contacting with the surface of said screen casing adjacent an end thereof.

4. The combination with a rollscreen assembly including a screen casing having a moulding along its upper edge and a guide track, of a casing supporting and track receiving device, comprising a supporting portion for said screen casing, a moulding portion and a track receiving portion said device having a groove formed therein between said supporting and said moulding portions, said groove being adapted to receive the guide track, said moulding portion of said device extending above the supporting portion thereof and contacting with a surface

of said screen casing adjacent the end thereof and forming a continuation of the moulding on said casing.

5. A device of the character disclosed comprising a supporting and receiving member adapted to be secured to the side of a window opening and extending from the sill to the top thereof, a screen casing adapted to be installed at the top of said opening and supported by said member and a screen guide track adapted to be received in said supporting and receiving member.

6. A device of the character disclosed comprising a supporting and receiving member adapted to be secured to the side of a window opening and extending from the sill to the top thereof, a screen casing adapted to be installed at the top of said opening and said member having a groove formed lengthwise therein, a guide track adapted to be received in said groove, the upper end of said member serving to support said screen casing.

7. A device of the character disclosed comprising a casing-supporting and track-receiving member having a groove and adapted to be secured to the side of a window opening and extending from the sill to the top thereof, a screen casing adapted to be installed at the top of said opening and a guide track adapted to be received in said groove, the upper end of said member serving to support said screen casing and having means to engage a surface of the screen casing and thereby retain it against displacement from the upper end of the member.

8. A track-receiving device comprising a channel-shaped supporting portion and a moulding portion formed of a single strip of material, the moulding portion being of a configuration to form an irregularly shaped channel and of greater length than said supporting portion, said channels opening in the same direction and defining between them, a channel opening in the opposite direction.

9. A casing supporting and track receiving device comprising a channel shaped supporting portion adapted to engage the lower surface of a casing and thereby supporting the same and a moulding portion integral therewith formed of a strip of material, the moulding portion being of a configuration to form an irregularly shaped channel, said channels opening in the same direction and defining between them, a channel opening in the opposite direction for the purpose of receiving a guide track.

10. A device of the class described comprising a single piece of metal formed to provide a supporting portion for one end of a screen casing and a moulding portion arranged to provide in conjunction with one edge of the supporting portion, a channel groove to receive a guide track for the side edge of a screen.

11. In combination with a roll screen as-

- sembly adapted to be mounted within a window opening including a screen casing arranged at one end of said opening and a guide track arranged at right angles to said screen casing, a device for supporting one end of said casing and receiving said guide track comprising a supporting portion to extend from the lower end of said opening to said casing and a channel groove formed in said device to receive said guide track.
12. A device of the character disclosed comprising an elongated piece of metal bent to channel form and adapted to be secured to a supporting surface with the flanges thereof contacting with the support whereby the web thereof is spaced from the support, a groove formed of the web portion of said metal, said groove opening away from said supporting surface.
13. A device of the character disclosed comprising an elongated piece of metal bent to channel form and adapted to be secured to a supporting surface with the flanges thereof contacting with the support whereby the web thereof is spaced from the support, a groove formed of the web portion of said metal, said groove opening away from said supporting surface, the portion of said metal on one side of said groove being of less length than the remaining portion thereof.
14. A device of the class described comprising a single piece of metal formed to provide a supporting portion and a moulding portion, said moulding portion and supporting portion being arranged side by side and slightly spaced to provide a channel groove for receiving a guide track for the side edge of a screen, said moulding portion projecting above said supporting portion.
40. Des Moines, Iowa, October 9, 1928.
